ICE CREAM FILLING MACHINE

Benton L. Tankersley, Fort Smith, Ark.

Application August 13, 1956, Serial No. 603,773

5 Claims. (Cl. 141—172)

This invention relates to a machine for filling cartons with bulk material as for example ice cream, the primary object being to provide apparatus that is automatic throughout the filling operation and capable essentially without operator attention of completely filling the cartons without spillage or other defects in operation, placing the cartons in condition for closure as the same emanate from the machine.

It is the most important object of the instant invention to provide a filling machine for ice cream cartons and the like having components for continuously and successively feeding the cartons to a position for raising into registering relationship with a material-feeding spout and thereupon lowering the filled carton onto a reciprocable support that removes the filled carton from beneath the spout clearing the space therebeneath for receiving another carton.

Another important object of the instant invention is the provision of a filling machine that employs a vertically reciprocable structure for handling the carton with respect to the material discharge spout and operable in connection with a horizontally reciprocable assembly that includes a pusher, as well as a slide operably interconnected and associated with the said structure in timed relationship thereto to feed the cartons to the structure and remove the same after filling.

A further object of the instant invention is the provision of a filling machine permitting continuous feeding of the material under pressure through the discharge spout by virtue of the fact that the empty cartons are fed therebeneath at a lower elevation than that of the reciprocable slide which receives the filled carton and withdraws the same from beneath the spout.

A still further object of the invention is to provide novel means for controlling the rate of descent of the carton under influence of the pressure of material emanating from the spout so that elimination of air pockets and complete filling of the carton is assured.

It is an important aim of the instant invention to provide fluid pressure means for controlling the vertical reciprocation of the carton handling structure utilized not only to cushion, and thereby control the rate of descent, but employed to withdraw a vertically reciprocable piston from beneath the filled carton when it comes to rest upon the horizontally reciprocable slide and to hold the piston in such position until an empty carton is deposited thereon.

Another aim of the instant invention is to provide means controlled by the vertical movement of the carton itself for in turn controlling the reciprocation of the empty carton pusher and the slide for withdrawing the filled carton from the piston and from beneath the spout.

Other aims and objects include the novel formation of the spout itself to assure elimination of air pockets; the way in which the fluid pressure assembly is controlled by parts of the mechanism for reciprocating the pusher and the slide; the way in which a pressure tank, together with pressure regulators, are provided to control the ver-

2

tical movement of the piston; the way in which the empty cartons are made available at all times to the pusher by a continuously moving conveyor; the manner of providing a series of carton grasping or holding dogs 5 on, and adjacent to, the horizontally reciprocable structure for assuring proper feeding and removal of the cartons with respect to the spout; and many other more minor aims and objects including important details of construction, all of which will be made clear or become apparent as the following specification progresses.

In the drawings:

Figure 1 is an end elevational view of an ice cream filling machine made pursuant to my present invention, parts being broken away for clearness.

Fig. 2 is a side elevational view thereof, parts being broken away to reveal details of construction.

Fig. 3 is an enlarged, fragmentary, plan view beneath the material feeding spout illustrating the conveyor and the horizontally reciprocable parts for feeding the cartons and withdrawing the same.

Fig. 4 is a view similar to Fig. 3 illustrating the horizontally reciprocable parts in another position.

Fig. 5 is a fragmentary, detailed cross-sectional view taken on line V—V of Fig. 4.

Fig. 6 is a schematic view illustrating the manner of operation of certain of the components, together with a wiring diagram showing the electrical features of the machine.

Fig. 6a is an enlarged view of the fluid control valve partially in section.

Figs. 7 to 11 inclusive are schematic views showing the sequence of operation from the time the carton is first fed to the spout until the filled carton is removed therefrom; and

Fig. 12 is an enlarged view partially in section showing a carton being filled with material emanating from the discharge spout.

The machine illustrated in the drawings and about to be described, has been especially adapted for filling conventional open-top ice cream cartons 14 with ice cream 16 emanating from an open bottom discharge spout 18, as best seen in Fig. 12 of the drawings. The cartons 14 are fed continuously along a horizontal path of travel into a position in front of a horizontally reciprocable pusher 20 by a continuous conveyor 22.

The conveyor 22 is driven by a prime mover such as an electric motor 24 shown in Figs. 1, 2 and 6, and which is operably connected with one of the shafts 26 through an idler shaft 28 by belt and pulley means 30 and chain and sprocket wheel means 32 (see Figs. 1 and 2). When the machine is placed in operation, switch 34 is closed to energize the motor 24 and thereby drive the conveyor 22 continuously as is clear in Fig. 6.

The pusher 20 is mounted on and supported by a horizontal bar 36 that reciprocates along a path of travel perpendicular to the path of the conveyor 22. Bar 36 also actuates an elongated, horizontally reciprocable slide 38 guided by tracks 40 as seen in Fig. 5. Figure 5 also illustrates the way in which bar 36 and slide 38 are interconnected through an arm 42 having pivotal connection with the plate 38 through a pin 44 depending from the latter.

A second electric motor 46 reciprocates the bar 36 and, therefore, the pusher 20, as well as the plate 38 through the medium of a crank 48, belt and pulley means 50, adjustable linkage 52 and 54, disc 56 and over-running clutch 58 that is in turn controlled by solenoid 60.

The link 52 pivotally interconnects the upper end of vertically swingable crank 48 with an ear 62 depending from the bar 36. The lowermost end of the crank 48 is pivotally connected with the disc 56 by the link 54, the connection between the link 54 and the disc 56 being

eccentric to the axis of rotation of the latter. Such eccentricity is adjustable by virtue of the fact that bearing 64 which receives the link 54, is slidably radially of the disc 56 within track means 66 rigid to disc 56. An adjusting screw 68 interconnecting the bearing 64 and the disc 56 permits shifting of the bearing 64 along the track means 66 toward and away from the axis of rotation of the disc 56, it being understood that disc 56 is driven from the over-running clutch 58.

A fluid pressure assembly is provided for receiving the empty cartons successively from the conveyor 22 and imparting vertically reciprocable movement thereto with respect to the spout 18. Such assembly includes a fluid cylinder 70 having a vertically reciprocable piston 72 therewithin that is in turn provided with an upstanding stem 74, and a small plate 76 rigid to the upper end of the stem 74. Manifestly, the piston stem 74 is aligned vertically with the axis of the spout 18 and moves toward and away from the open bottom of the latter when piston 72 is actuated.

A manifold 78 is coupled with a source of fluid under pressure such as air (not shown) through a feed line 80 having a pressure regulator 82 interposed therein. The lowermost end of the cylinder 70 is connected with the manifold 78 by a pipe 84 and the upper end of the cylinder 70 is connected with the manifold 78 by a pipe 86. A pressure tank 88 is connected to the pipe 84 by a branch 90 and a pressure regulator 92, together with a pressure gauge 94 are connected to the pipe 84 between the tank 88 and the manifold 78.

A valve 96 is interposed in the pipe 86 and as shown in Fig. 6a, the said valve 96 includes a tubular body 98 having a reciprocable spring-loaded plunger 100 extending into one end thereof. A roller 102 on the outermost end of the plunger 100 is held in constant engagement with the periphery of the disc 56 by spring 104 within the body 98 behind the plunger 100. When plunger 100 is in the position shown in Figs. 6 and 6a, fluid above the piston 72 is exhausted to the atmosphere by way of exhaust port 106 in body 98 communicating with the upper end of cylinder 70 by virtue of a cross bore 108 in plunger 100 registering with port 106, and an L-shaped passage 110 in plunger 100 interconnecting bore 108 and pipe 86.

Disc 56 is provided with a pair of segmental cams 112 and 114 on the periphery thereof successively engageable with the roller 102 when disc 56 rotates clockwise viewing Fig. 2, as indicated by the arrows. When the cam 112 depresses the plunger 100 to the innermost end of its path of travel as shown in Fig. 2, the bore 108 is placed in communication directly with the pipe 86, thereby interconnecting the manifold 78 with the upper end of the cylinder 70. When however, the disc 56 rotates to a position where the roller 102 engages the cam 114, plunger 100 moves outwardly under the action of spring 104 to a point intermediate the ends of its path of travel and in such position of the plunger 100, neither the bore 108 nor the passage 110 is in communication with either the pipe 86 or the port 106.

When the pusher 20 moves from the position shown in Figs. 3 and 7, to the position illustrated in Figs. 4 and 8, it removes a single carton 14 from the continuously operating conveyor 22 and slides such carton 14 onto the plate 76 directly beneath the spout 18. By virtue of the fact that the plate 38 is connected with the pusher 20 for reciprocation therewith, it is seen also that the said plate 38 moves to the right as depicted in Figs. 4 and 8.

The extent of movement of the carton 14 is, of course, governed by movement of the pusher 20 but in order to assure that the carton 14 is held properly aligned with the spout 18, the pusher 20 moves cartons 14 to a position embraced by a pair of swingable spring-loaded, arcuate fingers 116 seen best in Figs. 2 to 4 inclusive. A pair of parallel rails 118 guide the cartons 14 as the same are

advanced by the conveyor 22 and a pair of parallel plates 120 perpendicular to the rails 118 guide the cartons 14 as the same are advanced by the reciprocable structure 20-38.

The fingers 116 are mounted on the plates 120 and swingable about vertical axes 122. Upstanding pins 124, one on the innermost rail 118 and the other on the outermost plate 120, are provided with lateral extensions 126 serving as stops for the fingers 116. The said fingers 116 are yieldably biased toward each other by springs, rubber bands or the like 128, interconnecting the said fingers 116 and the upstanding pins 124, the said yieldable means 128 biasing the fingers 116 against the terminal ends of the extensions 126 when the pusher 20 and the plate 38 are in the position shown by Figs. 3 and 7.

The innermost end of the plate 38 is bifurcated as best seen in Figs. 3 and 4 to clear the piston stem 74 and its plates 76, presenting a pair of spaced-apart fingers 130. The fingers 130 swingably carry a pair of dogs 132 at their terminal ends for reciprocation with the plate 38. Short, upstanding carton-retaining panels 134 mounted on the fingers 130 adjacent their outermost edges and adjacent the terminal ends of the fingers 130, mount the dogs 132 for swinging movement toward and away from each other about vertical axes, and means such as rubber bands 136 interconnecting the dogs 132 and their corresponding panels 138, yieldably bias the dogs 132 inwardly toward each other. The L-shaped dogs 132 are employed to engage or grasp the filled carton 14 to pull the same along with the plate 38 from beneath the spout 18 during movement of the plate 38 from the position shown in Fig. 3 to the position shown in Fig. 4, as will hereinafter be more fully explained. The dogs 132 are shown in Fig. 4 engaging a filled carton designated by the numeral 14a.

After the plate 38 and its dogs 132 have moved the filled carton 14a to the position shown in Fig. 4, a pair of arms 138 engage the filled carton 14a to prevent its return movement toward the conveyor 22 with the return of the plate 38 to the position shown in Fig. 3.

The arms 138 are mounted for swinging movement on plates 120 about vertical axes 140 in substantially the same manner as fingers 116 are mounted on the plates 120, as seen in Figs. 2-4. Here again, through use of a lateral projection 142 rigid to the mounting means for the arms 138, the latter are yieldably biased inwardly toward each other by rubber bands or the like 144, interconnecting the projections 142 and the arms 138. Any suitable means (not shown) may be employed if deemed desirable or necessary, to limit the extent of inward swinging movement of the arms 138. The yieldable means 144 permit the arms 138 to swing outwardly when the slide 38 and its dogs 132 move the filled carton 14a from beneath the spout 18 to the position shown in Fig. 4. It is noted in Fig. 2 that the dogs 132 are disposed below the fingers 116 and the arms 138, whereby the dogs 132 may reciprocate freely with the plate 38 without interference by fingers 116 and arms 138. Notable in Figs. 7 to 11 inclusive, is the fact that the fingers 116 are disposed to remain in engagement with the carton 14 throughout the time the same is reciprocated vertically with respect to the spout 18 by operation of the piston 72 within cylinder 70. And, it is to be noted that fingers 116 readily yield outwardly to clear the carton 14a during removal from beneath the spout 18.

Motor 46 operates continuously upon closing of switch 146 (Fig. 6) but rotation of disc 56 and, therefore, reciprocation of pusher 20 and plate 38, are interrupted during each cycle of operation by energization of solenoid 60. Such energization is controlled by a switch 148 in series with the solenoid 60 and switch 146. A spring-loaded, horizontally reciprocable actuator rod 150 for controlling switch 148, is disposed within the path of travel of the carton 14 as the same is elevated onto the spout 18 in telescoping relationship thereto by upward

movement of the piston 72. As seen in Fig. 6, switch 148 is normally open but as soon as the uppermost edge of the carton 14 engages the rod 150 to shift the latter away from the spout 18, switch 148 is closed, causing solenoid 60 to remain energized until the carton 14 again descends to a position clearing the rod 150.

Manifestly, means (not shown) is provided for adjusting the rod 150 not only vertically to predetermine the period of time during which switch 148 is held closed, but horizontally toward and away from the spout 18 to accommodate cartons having differing wall thicknesses. The solenoid-controlled, over-running clutch 58 is conventional and, therefore, its details of operation are not illustrated. It may be pointed out merely that solenoid 60 controls a pawl forming a part of the clutch 58 to prevent its establishing a driving connection between belt and pulley means 50 and the disc 56 whenever solenoid 60 is energized.

The ice cream 16 is fed continuously under pressure to the spout 18 from a source of supply thereof (not shown) and the spout 18 is specially formed as shown in Fig. 12, to eliminate the formation of air pockets within the carton 14 and prevent complete filling thereof with the material 16. To this end, spout 18 has an appreciably greater outside diameter than inside diameter by virtue of its double-wall construction, presenting a dead-air space 152 to prevent formation and freezing of condensate on the outer surfaces of the spout 18. Alternately, the space 152 may be filled with a suitable insulation to thereby alleviate the freezing problem which would otherwise prevent escape of air from the carton 14 as indicated by arrows in Fig. 12.

In this respect, it is notable that the inside diameter of the carton 14 is slightly greater than the said outside diameter of spout 18. Notable also is that the outermost peripheral edge 154 of the spout 18 is beveled or rounded to assure guiding of the carton 14 onto the spout 18 when elevated by the plate 76 on piston stem 74.

Operation

It must be understood at the outset that certain conditions exist at all times for automatic operation of the machine above described.

First, the ice cream 16 is fed continuously under pressure through the spout 18. Secondly, the conveyor 22 operates continuously upon closing of the switch 146. By the same token, the prime mover 46 operates continuously upon closing of switch 146 except only during closing of the switch 148.

Additionally, fluid under predetermined pressure as controlled by regulator 82, is placed on the manifold 78 through line 80 at all times.

Finally, a predetermined pressure exists in the cylinder 70 beneath the piston 72 at all times determined by regulator 92 as indicated on the gauge 94.

With the above in mind, it is seen that the conveyor 22 feeds the cartons 14 continuously toward the outermost plate 20 and biases the same against such plate as conveyor 22 slides with respect to the row of cartons 14 held in place by the guide rods 118 as seen in Fig. 3.

Pusher 20 moves the proximal carton 14b from the conveyor 22 and slides the same onto the plate 76 by virtue of operation of motor 46. Viewing Fig. 2, it is seen that crank 48 is swung to the left-hand end of its path of travel when the pusher 20 is disposed as shown in Fig. 3. Clockwise rotation of the disc 56 exerts a pull upon the crank 48 through link 54 and crank 48 in turn pulls upon the bar 36 through link 52 to move bar 36, pusher 20 and plate 38 to the right. When these horizontally reciprocable parts are at the extreme right-hand end of their paths of travel, as shown in Fig. 4, the bearing 64 will have moved to the extreme left-hand end of its path of travel and be disposed adjacent the roller 102 of valve 96.

It is understood of course, that the piston 72 is at the

lowermost end of its path of travel as shown in Figs. 7 and 8, during the time that carton 14a is being shifted thereupon by the pusher 20. It is noted also in Figs. 4 and 8 that when the carton 14a is resting upon the plate 76 (which is incidentally at that time coplanar with the upper stretch of conveyor 22) the pusher 20 and the fingers 116 cooperate in grasping and holding the carton 14b in proper position for movement onto the spout 18. In this respect the pusher 20 is provided with an upstanding, arcuate flange 20a conforming to the contour of the carton 14a in the same manner as the arcuate configuration of the fingers 116.

Rotation of the disc 56, 180° as just described, moves the cams 112 and 114 to a position clearing the roller 102, thereby aligning the bore 108 with the port 106 and thereby exhausting the fluid above piston 72 from the cylinder 70 to the atmosphere. At that moment, i.e., moving of the plunger 100 to the position shown in Fig. 6a, pressure within the tank 88 and pipe 84 and, therefore, in the cylinder 70 below piston 72, causes the latter to move upwardly thereby raising the carton 14b in the manner illustrated by Fig. 6 and to the position shown in Fig. 9 telescoped on the spout 18.

During the initial upward movement of the carton 14b, and prior to its engagement with the rod 150 to close switch 148, the pusher 20 will have commenced its return movement toward the position shown in Fig. 3. This is by virtue of the fact that the bearing 64 commences its movement from adjacent the roller 102 toward the position shown in Fig. 2.

However, as soon as switch 148 is closed by the carton 14b, solenoid 60 will be energized to disengage the clutch 58 and rotation of disc 56 will be discontinued notwithstanding the fact that the prime mover 46 continues to operate.

As soon as piston 72 and, therefore, carton 14b reach the uppermost ends of their paths of travel, the force of the ice cream 16 emanating from the spout 18 and flowing into the carton 14, will cause the latter and, therefore, the piston 72, to move downwardly against the force of the fluid pressure existing in the tank 88, pipe 84 and cylinder 70 beneath piston 72.

It can now be seen that the rate of descent under the force of the ice cream 16 is determined by the pressure of fluid within the tank 88 as controlled by regulator 92.

Consequently, depending upon the viscosity of the ice cream 16, the weight thereof, the pressure for causing the same to flow through the spout 18, proper filling of the carton 14 may be assured by control of the fluid pressure in tank 88 through use of regulator 92 as guided by gauge 94. Manifestly, the pressure behind the ice cream 16 when considering its weight, is less than the pressure maintained in pipe 84 as read on the gauge 94, so that while the rate of descent is impeded, nonetheless, carton 14b will descend at substantially the same rate of flow of the ice cream 16 emanating from spout 18.

As soon as the upper edge of the carton 14b clears the rod 150, switch 148 opens to again interconnect the prime mover 46 with the sliding assembly 20-38, and prior to lowering of the carton 14b to the lowermost end of its path of travel, the fingers 130 of plate 38 will have returned to a position beneath the carton 14b to receive the same. At this point it is to be noted in Figs. 7 to 11 inclusive, that the plate 38 is disposed within a horizontal plane that is higher than the plane of the upper stretch of conveyor 22 and higher than the plate 76 when the latter is at the lowermost end of its path of travel.

Figure 10 illustrates the carton 14a resting on the fingers 130 with the upper edge of the carton 14a just clearing the lowermost edge of the spout 18. It is to be noted also that when the fingers 130 have returned to the position for receiving the filled carton, dogs 132 will likewise have been positioned behind the carton for engaging the latter and withdrawing the same from beneath the spout 18, through the fingers 116 as the latter

yield outwardly against the action of rubber bands 128 and as the plate 38 moves to the position shown in Fig. 4.

As the pusher 20 and plate 38 arrive at the position shown in Fig. 3 and, therefore, as the bearing 64 returns to the position shown in Fig. 2, cam 112 will engage the roller 102 thereby forcing the plunger 100 inwardly from the position shown in Fig. 6a, to a position where the bore 108 registers with the pipe 86. This action of the valve 96 directs fluid pressure from the manifold 78 to the cylinder 70 above the piston 72. Such pressure is higher than the pressure beneath the piston 72 and, therefore, the plate 76 is lowered from adjacent fingers 130 to the lowermost end of its path of travel, as shown in Fig. 10, rather quickly to clear the plate 76 for receiving another carton 14 from the conveyor 22.

The pressure is maintained upon the upper face of piston 72 throughout the time the cam 112 is in engagement with roller 102 and, therefore, throughout the time that an empty carton is fed by pusher 20 from the conveyor 22 to the plate 76. While the pusher 20 feeds an empty carton in this manner, the plate 38 simultaneously moves the filled carton 14a from beneath the spout 18, to a point of engagement by the terminal ends of the arms 138. The filled carton 14a moves freely between the arms 138 by virtue of the fact that they yield outwardly against the action of rubber bands 144. On the return movement of the plate 38 to the left-hand end of its path of travel, arms 138 hold the filled carton 14a and the plate 38 slides freely therebeneath. Any suitable means (not shown) may be provided to convey the filled cartons from the plate 38 to a point of placing lids thereon and further processing.

After the cam 112 moves to a position clearing the roller 102, cam 114 moves into engagement with roller 102, permitting outward movement of plunger 100 only to a point where the bore 108 is between pipe 86 and port 106. This takes the pressure off the upper face of piston 72 but does not permit it to rise under influence of pressure therebeneath since the fluid in the upper end of cylinder 70 cannot exhaust to the atmosphere by way of port 106 until cam 114 moves beyond roller 102 and spring 104 forces the plunger 100 to the position shown in Fig. 6a. By such construction, therefore, it is seen that the connection between manifold 78 and the cylinder 70 is blocked prior to exhausting of the cylinder 70 to the atmosphere and, therefore, there will be no flow of fluid from the manifold 78 to the atmosphere by way of port 106 during continuous operation of the machine.

The disposition of the plate 38 above the level of conveyor 22 and above the plate 76 when the latter is at the lowermost end of its path of travel, is important. First, as above indicated and as seen in Fig. 10, during movement of the filled carton from beneath the spout 18, the ice cream 16 will be wiped smoothly from the spout 18 establishing a level of the material in the carton flush with its uppermost edge.

Additionally, remembering that the ice cream 16 flows continuously during the interval of time between removal of the filled carton from beneath the spout 18 until an empty carton is placed thereon, a certain amount of the ice cream 16 will be forced beneath the lower edge of the spout 18. Consequently, when the empty carton is moved by the pusher 20 onto the plate 76, the upper edge of such carton will clear the partially discharged ice cream 16.

In this connection also the relative inside and outside diameters of the spout 18 becomes important for the diameter of such discharged ice cream will be appreciably less than the inside diameter of the carton 14. Consequently, when the latter is raised by the piston 72, no spillage will occur and there will be no tendency of the upper edge of the carton 14 shearing the ice cream 16 and causing the same to spill over the outside of the

carton 14. Still further, the double-wall construction of the spout 18 presents a space 156 beneath the lower edge of the spout 18 within the carton 14 as seen in Fig. 12 for progressive and gradual collection of air and discharge thereof upwardly as shown by the arrows between the carton 14 and the spout 18.

The amount of ice cream 16 that extends below the spout 18 as just above explained, depends of course, upon the speed of operation of the machine, all of which is controlled in part by regulation of the pressure in tank 88 as determined by regulator 92. In this connection, it is important to select the cushioning tank 88 and to determine its capacity in connection with the size of the cylinder 70. For the most part however, the cartons may be filled in rapid succession as fast as it is possible to force the ice cream 16 through the spout 18.

Having thus described the invention what is claimed as new and desired to be secured by Letters Patent is:

1. In a machine for filling cartons, an open bottom material-feeding spout; structure for raising the cartons into register with the spout to receive the material therefrom and for lowering the cartons as the same fill; reciprocable mechanism for feeding the cartons successively to said structure; apparatus connected with said mechanism for reciprocation therewith for removing the filled cartons successively from said structure; and means having parts disposed to be engaged by the cartons as the same are raised by said structure and while the cartons are being filled for preventing reciprocation of said mechanism and said apparatus during a predetermined period of operation of said structure.
2. In a machine for filling cartons, an open bottom material-feeding spout; vertically reciprocable structure for receiving said cartons singly, raising the same into register with the spout to receive the material therefrom and lowering the same during filling thereof; apparatus for removing the filled cartons from the structure including a horizontally reciprocable plate; and means for moving the plate to a position within the path of travel of the carton as the same descends during filling, and thereupon out of said position after the filled carton comes to rest on the plate to withdraw said filled carton from beneath the spout.
3. In a machine for filling cartons, an open bottom material-feeding spout; vertically reciprocable structure for receiving said cartons singly, raising the same into register with the spout to receive the material therefrom and lowering the same during filling thereof; apparatus for removing the filled cartons from the structure including a horizontally reciprocable plate; means for moving the plate to a position within the path of travel of the carton as the same descends during filling, and thereupon out of said position after the filled carton comes to rest on the plate; and means mounted on the plate for reciprocation therewith for engaging said filled carton as the same comes to rest on the plate whereby the plate exerts a pull on the filled carton to carry the same therewith and thereby withdraws the filled carton from beneath the spout as the plate moves out of said position.
4. In a machine for filling cartons, an open bottom material-feeding spout; vertically reciprocable structure for receiving said cartons singly, raising the same into register with the spout to receive the material therefrom and lowering the same during filling thereof; apparatus for removing the filled cartons from the structure including a horizontally reciprocable plate; means for moving the plate to a position within the path of travel of the carton as the same descends during filling, and thereupon out of said position after the filled carton comes to rest on the plate; means mounted on the plate for reciprocation therewith for engaging said filled carton as the same comes to rest on the plate whereby the plate exerts a pull on the filled carton to carry the same therewith and thereby withdraws the filled carton from beneath the spout as the plate moves out of said position; and means remote from

the spout and engageable with the filled carton after the same has been withdrawn from beneath the spout for preventing movement of the filled carton with the plate as the latter returns to said position.

5. In a machine for filling cartons, an open bottom spout for feeding material under pressure; a fluid pressure assembly beneath the spout having a cylinder, a piston reciprocable vertically in the cylinder toward and away from the spout and means on the piston for receiving a carton to be filled; reciprocable mechanism for feeding the cartons successively to said assembly while the piston is at said lowermost end of its path of travel; reciprocable apparatus for supporting the filled carton after the fluid is directed to the cylinder above the piston, said apparatus being movable to a position for withdrawing the filled carton from beneath the spout; a tank coupled with a source of fluid under pressure; means for directing the fluid from the tank to the cylinder beneath the piston to raise the latter and thereby move the carton into register with the spout; regulator means between the

20

tank and said source of fluid for maintaining the pressure in the tank below the pressure of the material whereby the latter lowers the carton and the piston at a predetermined rate as the carton fills with the material; means for directing the fluid from said source to the cylinder above the piston after the latter has descended a predetermined distance to lower the piston to the lowermost end of its path of travel; and means having parts disposed to be engaged by the cartons as the same are raised by said structure and while the cartons are being filled for preventing reciprocation of said mechanism and said apparatus during a predetermined period of operation of said structure.
